UNITED STATES PATENT OFFICE

GORDON E. ROEDDING AND ELMER C. OSBECK, OF GRAND RAPIDS, MICHIGAN, ASSIGNEES TO GRAND RAPIDS BRASS COMPANY, OF GRAND RAPIDS, MICHIGAN, A CORPORATION OF MICHIGAN

LATCH

Application filed July 6, 1926. Serial No. 120,711.

The present invention relates to latches for refrigerator doors and the like; and its object is to provide a latch having improved means for yieldingly holding the latching bolt in certain positions, and, in certain movements of the bolt, urging the same into one of its positions.

This and any other objects hereinafter appearing are attained by, and the invention finds preferable embodiment in, the structure hereinafter particularly described in the body of this specification and illustrated by the accompanying drawings, in which:—

15 Figure 1 is a front view of a latch and its keeper element;

Figure 2 is a left hand side view thereof;

Figure 3 is an inner side view of the latch, showing the bolt in latching position;

20 Figure 4 is a like view of the same, but showing the bolt in retracted position;

Figure 5 is a transverse sectional view of the latch taken on line 5—5 of Figure 3;

Figure 6 is a transverse sectional view of 25 the same taken on line 6—6 of Figure 3;

Figure 7 is a left hand side view of the latch and its keeper element, showing the door member on which the latch is mounted approaching closed position; and

30 Figure 8 is a view of a bolt-actuating spring.

In the embodiment of the invention illustrated by the accompanying drawings, a latch is shown mounted on the closure member 1 of a door, its keeper element 2 being mounted on the jamb or frame member 3 of the door. This latch comprises a latching bolt 4 swingably mounted on the pivot post 5 and enclosed in a casing 6, a portion 35 7 of the bolt extending through a slot 8 in the casing and being adapted to latchingingly engage in the keeper or recess 9 in the element 2 to hold the closure member 1 shut, said portion 7 being desirably provided 40 with an anti-friction roll 10. This latching bolt 4 may be swung by any suitable means; preferably however, a lever 11 of common form fulcrumed at 12 on the casing and having a handle arm 13 and a short arm 14 45 extending through an opening 15 into the

casing is provided, said short arm engaging in a notch 16 in the latching bolt to swing the bolt in either direction.

A U-shaped spring 17 has its laterally extending ends 18 and 19 rockable in bearings 20 and 21 in the casing and in the bolt respectively. This spring presses the bolt in such manner as to yieldingly hold the same in either its keeper-engaging position or its retracted position, and to urge the bolt to 55 one position or the other as the case may be, whenever in the bolt's swinging movement its bearing 21 passes across a direct line extending between the casing's bearing 20 and the pivot post 5.

When the closure member 1 is moved to nearly closed position, the roll 10 strikes the inclined portion 20 of the element 2 and is thereby moved downwardly into latching engagement with the keeper or recess 9.

The invention being intended to be pointed out in the claims, is not to be limited to or by details of construction of the particular embodiment thereof illustrated by the drawings or hereinbefore described.

What is claimed is:

1. In combination with a keeper, a latch comprising: a bolt swingably mounted on a door member and movable to latching position in the keeper and to retracted position; a U-shaped spring pivotally secured at one end on the bolt and yieldingly holding the bolt in one of its said positions, and at a point in the bolt's movement urging the same to the other of its said positions.

2. In combination with a keeper, a latch comprising: a bolt swingably mounted on a door member and movable to latching position in the keeper and to retracted position; a spring having its ends pivotally secured on said member and on the bolt respectively and yieldingly holding the bolt in one of its said positions, and at a point in the bolt's movement urging the same to the other of its said positions.

3. In combination with an element having a keeper and a bolt-moving inclined portion, a latch comprising: a bolt swingably mounted on a door member and movable to latching position in the keeper and to re-

tracted position, being when retracted movable into latching position by striking said inclined portion; a U-shaped spring having its ends rockably mounted on said member and on the bolt respectively and yieldingly holding the bolt in one of its said positions, and at a point in the bolt's movement urging the same to the other of its said positions.

4. In combination with a keeper, a latch comprising: a bolt swingably mounted on a door member and movable to latching position in the keeper and to retracted position; a spring having its ends pivotally connected to said member and to the bolt respectively and yieldingly holding the bolt in one of its said positions, and at a point in the bolt's movement urging the same to the other of its said positions.

5. In testimony whereof we have hereunto set our hands at Grand Rapids, Michigan, this 30th day of June, 1926.

GORDON E. ROEDDING.
ELMER C. OSBECK.
